ASSIGNORS TO TRUCK, TRACTOR AND MANUFACTURING COMPANY, OF ST. LOUIS,
MISSOURI, A CORPORATION OF MISSOURI.

BELT-LACING TOOL.

1,391,736.

Specification of Letters Patent. Patented Sept. 27, 1921.

Application filed July 12, 1920. Serial No. 395,668.

To all whom it may concern:

Be it known that we, ISIDOR M. JACOBS and WILLIAM CRAMER, citizens of the United States, residing, respectively, at the city of 5 Kansas City, in the county of Jackson and State of Missouri, and at the city of St. Louis, State of Missouri, have invented certain new and useful Improvements in Belt-Lacing Tools, of which the following is a 10 specification.

This invention is a tool for applying belt lacings to belts. It is especially intended and adapted for use in connection with a well-known and standard form of staples 15 used for belt lacings.

An object of the invention is to provide a tool which can be constructed at a minimum cost, and which will be efficient in use.

A further object of the invention is to 20 provide a tool in which the belt is securely clamped against displacement so that the staples will be properly placed therein.

A further object is to provide simple clamping means to hold the belt, and also 25 the staples.

In the accompanying drawings forming part of this specification, in which like numbers of reference denote like parts wherever they occur,

30 Figure 1 is a top plan view;

Fig. 2 is a side elevation;

Fig. 3 is a side elevation with a hammer about to clench the staples;

Fig. 4 is a longitudinal vertical sectional view;

Fig. 5 illustrates a staple in a piece of belting;

Figs. 6 and 7 illustrate a modification; and

40 Figs. 8 and 9 depict another modification.

The staples 1 are placed in the jaw 2 having a plurality of teeth 3. The end of the belt 4 is then passed between the upper points 5 and the lower points 6 of the staples 1, and between the wedge 7 and the keeper 8. The wedge 7 is driven home. The pin 9 is inserted as soon as the staples 1 are inserted in the jaw 2.

With the parts in the position shown in 50 Fig. 3, the ordinary hammer 10 is used and clenches the staples 1 into the shape shown in Figs. 5 and 1.

After this, a twill of twisted rawhide or the like (not shown in the drawings) is

passed through openings 11 in all the staples 55 1 causing them to meet together and overlap from opposite pieces of belting brought together end to end.

The teeth 3 are preferably formed by saw cuts along the bend of a U-shaped plate 12 60 and a plate 14 is so disposed between the arms of the U-shaped plate 12 as to provide an eye for the passage of the pin 9.

Plates 12 and 14 are attached to the plate or anvil 15 by rivets 16 or other suitable 65 means.

The jaw teeth 3 hold the staples 1 quite steadily for the impact of the hammer 10, but the object of the modifications depicted in Figs. 6 to 9 is to afford a brace for them 70 so that they will be more steadily held. Such brace or steadyng device takes the form in Figs. 8 and 9 of the wedge 16', which, when driven home as shown in Fig. 8, holds the staples 1 very firmly and steadily while the 75 same are being hammered by hammer 10.

The said brace or steadyng device in Figs. 6 and 7 is in the form of a thumbnut 17 which applies pressure to plate 12 and causes the same to press the lower part of the 80 staples against the plate or anvil 15.

In Figs. 6 and 7 the anvil or plate 15 is shown as provided with an integral upturned front portion 18 which coöperates with a clamp 19 pivoted at 20 on a pin 21 85 that runs through a bend of the anvil 15 to hold the belt 4, thereby preventing displacement of the same during the stapling operation. In use, belt 4 will be fed between the upturned portion 18 and the strap 90 22 of clamp 19. Plate 12, in Figs. 6 and 7 especially, is more or less resilient and therefore responds to the action of the thumbscrew 17, thereby causing the teeth 3 to press upon the staples 1, holding the same steady. 95

The thumbscrew 17 consists of the winged nut 23, the screw 24, and the clamping member 25, the latter being adapted to press on rod 26 that extends from one side to the other of the clamp 19. Turning nut 23 100 down on screw 24 causes clamping member 25 to press on rod 26 and thus to clamp the belt between clamp 19 and the upturn 18.

It is to be understood that the constructions depicted in Figs. 6 and 7 and 8 and 9 105 can be united in one, that is to say, wedge 16' may be placed in the device illustrated in Figs. 6 and 7.

Having thus described this invention, we hereby reserve the benefit of all changes in form, arrangement, order, or use of parts, as it is evident that many minor changes may be made therein without departing from the spirit of this invention or the scope of the following claims.

We claim:

- 10 1. A belt lacing device comprising a plate having staple receiving means, a staple retaining pin passed through said plate, a clamping device engaged with said plate to hold the staple retaining pin in position, a U-shaped belt holding member having a cross rod engaged by said clamping device, and tensioning means for said clamping device.
- 15 2. A belt lacing device comprising a plate having staple receiving means, a staple retaining pin passed through said plate, a clamping device engaged with said plate to hold the staple retaining pin in position, a U-shaped belt holding member having a cross rod engaged by said clamping device, tensioning means for said clamping device, and
- 20 25 3. In a belt lacing device, the combination

of a U-plate having teeth at its bend, and arranged to hold staples between the teeth, a removable pin securing the staples within the U-plate, a member arranged to advance 30 along an inclined plane to clamp said staples against displacement, means to hold the belt securely against displacement, and an anvil on which the staples are to be clenched in said belt.

35 4. In a belt lacing device, the combination of a U-plate having teeth at its bend, and arranged to support staples between the teeth, a removable pin securing the staples within the U-plate, a screw operated clamp 40 engaging the plate to hold said pin in position, a belt holding means to securely hold a belt against displacement and in operative relation to the staples, said belt holding means operated by said screw clamp, and an 45 anvil on which the staples are to be clenched in said belt.

In testimony whereof we hereunto affix our signatures.

ISIDOR M. JACOBS.
WM. CRAMER.
